UNITED STATES PATENT OFFICE.

FRED L. MCGAHAN, OF INDIANAPOLIS, INDIANA.

BOILER-FLUE CLEANER.

SPECIFICATION forming part of Letters Patent No. 365,836, dated July 5, 1887.

Application filed September 25, 1886. Serial No. 214,513. (No model.)

To all whom it may concern:

Be it known that I, FRED L. MCGAHAN, a citizen of the United States, residing at Indianapolis, in the county of Marion and State 5 of Indiana, have invented a new and useful Improvement in Boiler-Flue Cleaners, of which the following is a specification.

My invention relates to improvements in a boiler-flue cleaner for which Letters Patent 10 No. 313,509 were issued to me March 10, 1885. Said flue-cleaner is of that class in which the flue is cleaned by means of a jet of steam discharged through a suitable nozzle, by means of which it is directed against and 15 along the interior walls of the flue, the discharge of the steam into the flue being controlled by means of a valve which is automatically closed by the steam-pressure when the cleaner is removed from the flue.

20 The objects of my present improvements are to provide guides by which the nozzle may be easily brought to its proper position in the mouth of the flue, to more perfectly exclude cold air from the interior of the flue while the 25 cleaner is in operation.

The accompanying drawings illustrate my invention.

Figure 1 represents a side elevation, a portion 30 of the valve-chamber being broken away. Fig. 2 is a front elevation of the nozzle and guide. Fig. 3 is a central longitudinal section.

A is the nozzle, having a series of narrow annular discharge-ports, b b b b.

35 B is a tapered annular plate adapted to slide over the nozzle, and connected by four arms (not shown) with a central hub, c, which is secured by a nut, d, to the valve-stem e.

F is the valve, which is opened by the backward movement of the plate B, thus allowing 40 the steam to pass from the steam-chamber h to the ports b.

H is a tube connecting the steam-chamber h with a T-coupling, i, to one branch of which 45 is connected the hose j, which leads from the boiler or other source of steam-supply. A rod, k, is secured in the other branch of the coupling and serves as a handle.

The parts thus far described are all shown 50 in my above-mentioned Letters Patent.

For the purpose of guiding the nozzle while

entering the flue, I form integral with the plate B a conical frame consisting of the converging bars l l l l, projecting beyond the nozzle. The arrangement is such that said bars 55 are between the ports b, and they therefore allow the steam-jet to pass freely between them.

For the purpose of making a close joint between the face of ring B and the end of the 60 flue, and therefore more thoroughly excluding cold air, I insert in the face of the ring another annular ring, I, of rubber or other elastic packing.

The hose j is secured to coupling i by means 65 of a clamp, N o P, which will form the subject-matter of another application. Steam, being admitted to the hose-tube H and steam-chamber h, is retained therein by valve F. The conical guide-frame, consisting of the 70 converging bars l, is inserted and pushed into the open end of the boiler-flue until the face of the elastic ring I comes in contact with and effectually closes the end of the tube. A quick thrust forward now causes the nozzle to slide 75 through plate B until arrested by the flange s. Valve F, being rigidly secured by means of its stem to the plate B, is thus opened, and the steam flows in annular jets through the ports b. As soon as the nozzle is withdrawn, valve 80 F is closed by the steam-pressure.

I claim as my invention—

1. In a flue-cleaner of the class described, the combination, with the nozzle having annular discharge-ports and the valve-actuating plate, of the guide-frame consisting of a series of converging bars secured to said plate, arranged between said ports and projecting beyond said nozzle, substantially as and for the purpose specified. 90

2. In a flue-cleaner, the combination, with the nozzle A, valve F, and plate B, of the series of converging bars formed integral with said plate, substantially as and for the purpose specified. 95

3. In a flue-cleaner, the combination of the plate B, having bars l, and the annular elastic packing-ring I, for the purpose specified.

FRED L. MCGAHAN.
